CLAIM

The ornamental design for a micro fluidic glass chip interface bracket, as shown and described.

DESCRIPTION

The invention was made with government support under Contract No. DE-AC05-00OR22725 awarded by the U.S. Department of Energy. The government has certain rights in the invention.

FIG. 1 is a perspective view of a microfluidic glass chip interface bracket showing our new design;

FIG. 2 is a front view thereof;

FIG. 3 is a right side view thereof, the left side view being a mirror image thereof;

FIG. 4 is a back view thereof;

(Continued)

FIG. 5 is a top view thereof; and,
FIG. 6 is a bottom view thereof.
The left side view is a mirror image of the right side view.
